X-RAY PLATE AND FILM MARKER

Robert Knight, Seneca Falls, N. Y.

Application November 1, 1929, Serial No. 404,054

10 Claims. (Cl. 250—34)

This invention relates to a film marker adapted to be used by X-ray specialists in the process of making X-ray pictures of parts of the human anatomy and other objects for photographically impressing upon the photographic plates or films any desired identification characters and serial number of each particular case together with such other information as may be required for future reference.

10 In the use of devices of this character it is important that all of the type shall be disposed in a flat plane substantially normal to the X-rays or at least parallel with and in close proximity to the supporting-plate upon or near which the object or objects including the type-plates are adapted to be supported during the photographing process.

20 One of the main objects, therefore, of the present invention is to provide a simple and comparatively inexpensive marker in which all of the type shall be held in fixed relation to each other and in substantially the same plane or in juxtaposed parallel planes so that the marker unit may be placed flatwise upon or adjacent the object supporting-plate to enable its reference characters of ray-impervious material to be photographically impressed upon the photographic plate or film simultaneously with the impression of the principal object.

30 In other words I have sought to provide a more economical means for supporting the individual type in proper position for photographic reproduction on the photographic plate or film than has heretofore been practiced and to enable the individual type to be selected and arranged in such relation as may be desired as distinguished from the collective rearranging of the type either by stenciling or unitary combinations of the type.

40 Other objects and uses relating to specific parts of the device will be brought out in the following description.

In the drawing:

Figure 1 is a perspective view of an X-ray marker embodying various features of my invention.

45 Figure 2 is an enlarged longitudinal sectional view of the same taken in the plane of line 2—2, Figure 1.

Figure 3 is an enlarged transverse sectional view 50 taken in the plane of line 3—3, Figure 1.

55 Figure 4 is a perspective view of the detached holder for the type plates.

Figure 5 is a perspective view of the detached keeper plate for retaining the type plates flatwise in the holder.

Figure 6 is a perspective view of the laminated type plate showing a portion of one of the layers broken away to reveal the type.

Figure 7 is a perspective view of one of the individual type sections.

Figure 8 is a face view of a photographic plate with the informative matter of the type plates reproduced thereon.

As illustrated this X-ray marker comprises a substantially rectangular holder 1 of ray-permeable material such as aluminum elongated in one direction and provided with a substantially flat bottom portion back-plate 2 and opposite upright side portions 3 extending along the longitudinal edges of the bottom portion 2 and provided with inturned lengthwise flanges 4 forming longitudinal grooves 5 which also extend along the longitudinal edges of the bottom plate as shown more clearly in Figure 4, the flanges 4 being relatively narrow to leave a clear open space between them and together with the grooves form a lengthwise guide for the type bearing sections presently described.

Associated with the holder 1 is a laminated rectangular type-bearing plate 6 of about the same length and width as the bottom 2 of the holder 1 and composed of relatively thin layers 7 and 8 of different ray-permeable material such for example as celluloid and fabric adhesively secured together face to face and adapted to receive between them opposite rows of type 9 and 10 which are arranged adjacent the opposite lengthwise edges of the plate 6 in transversely spaced relation.

These type, 9 and 10, are preferably made in separate units of lead or other ray-impenetrable material, said units being arranged in sequence along the opposite lengthwise edges of and between the layers 7 and 8 and adhesively secured to the layer 7 or to both layers which serve to hold the type in fixed relation so that when the laminated plate 6 is inserted in the grooves 5 of the holder 1 the opposite rows of type 9 and 10 will underlie the flanges 4, the row of type 9 indicating, in this instance, the doctor having the case in charge while the row of type 10 indicates the address of the doctor.

When the laminated plate 6 is inserted in proper position in the holder 1 a flat slide or keeper plate 11 of relatively thin ray-permeable material, such as aluminum, of slightly greater length than and of about the same transverse width as the bottom 2 of the holder 1 will be inserted endwise in the grooves 5 across the outer surface of the laminated plate 6 to hold 55

the latter flatwise in said holder against buckling and substantially parallel with the bottom 2.

5 The opposite ends 12 of the slide 11 projecting beyond the corresponding ends of the bottom 2 of the holder 1 will then be bent downwardly and longitudinally under the adjacent portions of said bottom to hold the slide and laminated plate 6 against endwise displacement from the holder.

- 10 After the laminated plates 6 and slide 11 have been placed in operative position in the manner described additional type plate sections 13 of substantially the same width as the bottom 2 of the holder 1 are slidably inserted in sequence 15 from one end into the guide grooves 5 between the outer surface of the type plate 6 and flanges 2, each section 13 being provided with identification type 14 of lead or equivalent ray-impervious material adhesively secured thereto substantially midway between the opposite longitudinal edges thereof so that when the sections are placed sequentially in different positions in the holder the type 14 will be outermost.

25 These identification type 14 may be letters or figures or a combination of letters and figures which, when photographically impressed upon the photographic plate as A, will be reproduced in the same order or relation for identification of the case under the designated doctor's care.

- 30 The letters 14 on one or more of the type plate sections 13 may indicate the righthand or left-hand portion of the anatomy of the object operated upon while the remaining numbers 14 indicate the serial number of the particular case 35 under treatment which in turn may, through other records, identify the subject operated upon.

40 All of the type 9 and 10 and 14 are made of lead or equivalent material which is impenetrable by the X-rays used in the photographic process while all of the other parts of the device are pervious to the X-rays, the photographic reproduction of the type 9, 10 and 14 being indicated on the photographic plate or film A as 9', 10', and 14'.

45 Operation

50 The individual type 9 and 10 are adhesively applied to one of the surfaces of the celluloid or equivalent layer 7 in the order shown in Figure 6, after which the fabric or equivalent layer 8 is adhesively applied to the same surface of the layer 7 and to the corresponding surface of the type 9 and 10 thus completing the type plate 6.

55 This type plate 6 is then inserted endwise into the grooves 5 of the holder 1 as shown more clearly in Figure 2 after which the slide 11 is placed in operative position in the grooves 5 and its ends bent down and under the corresponding ends of the bottom 2 to hold the laminated plate 6 against endwise displacement from the holder.

60 The type plate sections 13 with the type 14 thereon are then placed in operative position within the holder 1 in the order shown in Figure 1, thus bringing the type 14 in a line between the rows of type 9 and 10, the slide 11 serving as a back support for the sections 13 to hold the latter in a substantially flat plane.

65 It is now evident that when the type plate 6 bearing the name and address of the doctor having the case in charge is placed in operative position within the holder 1 it will be held in such position by the slide 11 and may remain in such position for further use with additional cases by 70 the same doctor.

75 It will be noted, however, that the type bearing sections 13 with the type thereon are freely slideable by hand in the grooves 5 of the holder 1 and may be changed for each new case by simply sliding the sections endwise from the holder and replacing them with other identification characters so that each case may be identified by its serial number while the letter type may serve to indicate to the attendant or physician the particular position, right or left, of the 10 anatomical part being treated.

What I claim is:—

1. An X-ray plate and film marker comprising a holder having inturned flanges along its opposite lengthwise edges forming lengthwise grooves, 15 a plate having its opposite lengthwise edges engaged in said grooves and provided with rows of type along said edges, and separate type-bearing sections having their opposite lengthwise edges slidably engaged in said grooves and their type 20 disposed between said opposite rows of type.

2. An X-ray plate and film marker comprising a holder having inturned flanges along its opposite lengthwise edges forming lengthwise grooves, 25 a laminated plate having its opposite lengthwise edges engaged in said grooves and provided with rows of type along said edges, an additional plate engaged in said grooves and extended across the outer face of the laminated plate, and type-bearing sections slidably engaged in said grooves 30 and extending across the outer face of the additional plate.

3. In a film marker, a holder elongated in one direction and provided with opposite lengthwise grooves, a type plate having its opposite edges 35 engaged in said grooves, and a keeper-plate extended along the outer face and beyond the opposite ends of the holder and type plate and offset across said ends to hold said holder and type plate against relative endwise movement. 40

4. A film marker for use in making X-ray pictures comprising an elongated plate of ray-permeable material, rows of type of ray-impermeable material secured to the plate along opposite lengthwise edges thereof, and a holder in which 45 the plate is removably mounted having opposite lengthwise flanges overlying the adjacent rows of type.

5. A film marker for use in making X-ray pictures comprising a holder, a laminated plate removably mounted in the holder and composed of layers of ray-pervious material, and ray-impermeable type-members arranged between the layers of the plate.

6. A film marker for use in making X-ray pictures comprising a holder having opposite guide grooves and two flat imperforate ray-pervious layers superposed flatwise one upon the other and inserted in said grooves, and ray-impermeable type members between said layers. 60

7. In a film marker of the character described, the combination with an elongated holder having opposite lengthwise grooves, of a laminated plate composed of layers having their opposite lengthwise edges inserted in said grooves, and type members interposed between said layers.

8. In a film marker of the character described, the combination with an elongated holder having opposite lengthwise grooves, of a plate having its opposite edges engaged in said grooves, and type- 70 supporting members inserted in said grooves and resting upon the outer surface of said plate.

9. In a film marker of the character described, the combination with an elongated holder having inturned flanges along its opposite lengthwise 75

edges, of a plate mounted in the holder and provided with opposite rows of type underlying the corresponding flanges, a second plate overlying the first plate, and type-supporting members overlying the second plate and having its opposite edges underlying the corresponding flanges.

10. A device for marking X-ray films comprising a rectangular holder, said holder being substantially flat and having its opposite longitudinal edges turned upwardly and inwardly to form plate receiving channels, a laminated plate having its opposite longitudinal edges in engagement with said channels, rows of ray-impervious type se-

cured along the opposite lengthwise edges of said laminated plate between the layers thereof, a keeper-plate overlying said laminated plate, said keeper-plate extending beyond the opposite ends of said holder and laminated plate and being bent downwardly across said ends for holding said holder and laminated plate against relative endwise movement, and type bearing sections slidably engaged in said channels and adapted to overlie said keeper-plate, said sections having ray-10 impervious type thereon normally disposed between the inturned edges of said holder. 5

ROBERT KNIGHT.
